COMBINED SIGN AND CLOCK

Theophile L. de Zinno, Miami, Fla., assignor to Advertime Corporation, Miami, Fla., a corporation of Florida

Filed Dec. 28, 1967, Ser. No. 9,955

Term of patent 14 years

Int. Cl. D10—04; D20—03

U.S. Cl. D96—12

The figure is a perspective view taken from the top and one side of a combined sign and clock showing my new design, the opposite side and bottom being essentially the same as the side and top shown.

The dominant features of my design reside in the portions shown in full lines, it being understood that the broken line showing of letters, a bottle and glasses are for purposes of illustration only.

I claim:

The ornamental design for a combined sign and clock, as shown and described.
